CLAIM

The ornamental design for a plug, as shown and described.

DESCRIPTION

FIG. 1 is a rear perspective view of a plug design showing my new design.

FIG. 2 is a front perspective view of a plug.

FIG. 3 is a front view of a plug.

FIG. 4 is a rear view of a plug.

FIG. 5 is a left side view of a plug.

FIG. 6 is a right side view of a plug.

FIG. 7 is a top view of a plug; and,

FIG. 8 is a bottom view of a plug.

Any shading and cross-hatching are not features of the design but are utilized to illustrate the surface contours of the plug design in the drawings.

In the drawings, the broken lines are for the purpose of illustrating portions of the plug and form no part of the claimed design.
